UNITED STATES PATENT OFFICE.

ADOLFO DE CLAIRMONT, OF TOLEDO, OHIO.

IGNITION-INDICATING DEVICE FOR INTERNAL-COMBUSTION ENGINES.

1,084,397.

Specification of Letters Patent.

Patented Jan. 13, 1914.

Application filed December 6, 1911. Serial No. 664,287.

To all whom it may concern:

Be it known that I, ADOLFO DE CLAIRMONT, a citizen of the United States, residing at Toledo, in the county of Lucas and State of Ohio, have invented certain new and useful Improvements in Ignition-Indicating Devices for Internal-Combustion Engines, of which the following is a specification.

10 It is well known that drivers of automobiles have heretofore experienced considerable difficulty, whenever the engine misses fire, or whenever one of the cylinders fails to explode, it being then necessary for 15 the operator to get out of the car and open the hood of the engine and test the various spark plugs and wiring in order to ascertain which cylinder is missing, which may be caused, as is well known, by defective 20 wiring, sooted spark plugs, and various other causes.

I have observed that most drivers, whenever a cylinder misses, drive the car through to the end of their destination, trusting to 25 chance to have the cylinder refire, and in such event, the cylinder that is missing, becomes sooted over with unburned gasoline and carbonizes from the excess of oil flowing through without explosion from the 30 heat of the cylinder, whereby the spark plugs and valves become sooted and the engine more or less severely injured.

With a knowledge of these conditions, my 35 invention, broadly considered, aims to overcome these difficulties by the provision of a device whereby the operator of an automobile or the like may have in front of him, on the dash board, a cabinet containing a number of glass tubes, the number varying 40 according to the number of cylinders, the parts being so arranged that at the instant of the explosion in each cylinder, there will occur in the corresponding glass tube, a flash of light *in vacuo*.

45 Specifically considered, my invention consists of a number of glass tubes incorporated in the wiring system of the engine and containing a rarefied gas, in the nature of Geisler tubes, designed to become luminous 50 at the instant the explosion occurs in the cylinder corresponding to a tube, whereby the driver may at all times be kept in full knowledge of the working of the various cylinders, the tubes being preferably contained in glass cylindrical casings which

may be filled with different colored liquids, so as to contrast the electrical flash or luminous interval. And the invention also consists in certain constructions and arrangements of the parts that I shall hereinafter 60 fully describe and claim.

For a full understanding of the invention, reference is to be had to the following description and accompanying drawing, in which:

Figure 1 is a face view of one embodiment 65 of my invention; Fig. 2 is a transverse sectional view through the box or cabinet containing the tubes, and; Fig. 3 is a diagrammatic view.

Corresponding and like parts are referred to in the following description and indicated in all the views of the drawing by the same reference characters.

In carrying out my invention, I provide 70 a number of glass tubes 1, the number varying with the number of cylinders comprising the engine, said tubes being preferably helical in form, as shown, and provided at their ends with bulbs 2, in which terminals 80 or electrodes 3 are hermetically sealed, the outer ends of the terminals projecting from the bulbs, as clearly illustrated in Fig. 2. These tubes are exhausted as much as possible of atmospheric air and I prefer to 85 charge them before exhausting with hydrogen, or oxygen, sulfuric acid gas or other mineral coloring vapors, whereby there is left a very slight trace of the gas which colors the electrical flash passing 90 through the partial vacuum.

I preferably inclose each tube 1 in a protective cylindrical casing 4 of glass, said casing containing, if desired, a colored liquid containing a suitable dye in order to 95 contrast the electrical flash. The ends of the protective cylinders or casings 4 may be sealed, as at 5, by plaster of Paris or some similar substance, said ends being capped, as at 6. Binding posts 7 pass in through the 100 ends of the casings into contact with the terminals 3, and wires 8 lead from the magneto or other source of electrical supply and are connected to the corresponding binding post 7 of the respective tubes 1, 105 other wires 9 leading from the opposite binding post of the respective tubes to the spark plugs 10 of the various cylinders of the engine.

In the preferred arrangement of the parts, 110

the tubes and their protective casings are mounted in a case or cabinet 11 and are exposed to view through the open front of the cabinet, the cabinet being provided, preferably, with a hinged top and bottom, whereby access may be readily had to the binding posts. Manually operable switches 12 are mounted on the case 11 and, as best illustrated in Fig. 3, are designed to directly 10 connect the lower binding post 7 with the spark plugs 10 through the instrumentality of wires 12^a, whereby any tube may be cut out, should it become broken.

It will of course be understood that the 15 wires 8 leading from the magneto or the like, pass as a cable 13 into the box or cabinet 11 and that the wires leading from the tubes pass to the spark plugs by a corresponding cable 14, as indicated in Fig. 1.

From the foregoing description in connection with the accompanying drawing, the 20 operation of my improved visible spark system for internal combustion engines will be apparent.

In the practical use of the device, the 25 switches 12 being open, the tubes 1 will become luminous at the instant of the explosion in the cylinder, whereby the driver of the car may at all times be kept in full 30 knowledge of the conditions of the sparking system and at once determine, should the occasion require, which of the cylinders is failing to fire. No alterations are necessary, as the device can be easily wired and attached to any make of car, using gasolene 35 as the motive power and the engine of which is fired by a storage cell, dry cell, magneto or induction coils.

The device will manifestly increase the 40 efficiency of the engine, which will effect a saving of gasolene or other hydrocarbon used, as it will produce positive explosions on fairly weak mixtures, and furthermore, the life of the engine will be increased, for 45 the reason that there will be a uniform impulse on each cylinder at its proper cycle or period, thus preventing the strain which

is imposed on an engine when it is running on only some of its cylinders.

It is to be understood that my invention 50 is not limited to the precise details of construction shown in the accompanying drawing, but that various changes may be made in the construction, arrangement and proportions of the parts without departing 55 from the scope of the invention as defined in the appended claims.

Having thus described the invention, what is claimed as new is:

1. A device for indicating ignition in multiple cylinder explosive engines comprising a cabinet having open front and hinged ends, supporting webs extending across the opposite ends of the cabinet, a plurality of transparent cylinders mounted between and 60 extending through said supporting webs, a plurality of helical vacuum tubes arranged one within each of the transparent cylinders, oppositely disposed terminals in each of said tubes, and binding screws passing into the 65 ends of each transparent cylinder and engaging the corresponding terminals.

2. A device for indicating ignition in multiple cylinder engines comprising a cabinet 75 having open front and hinged ends, supporting webs extending through the cabinet, parallel to the hinged ends, a plurality of transparent cylinders passing through said supporting webs and having closed ends, a plurality of vacuum tubes supported one in 80 each of the cylinders, a pair of oppositely disposed terminals passing into the opposite ends of each vacuum tube, binding screws disposed in conjunction with the opposite 85 end of each cylinder and having electrical connection with the terminals in the vacuum tubes.

In testimony whereof I affix my signature in presence of two witnesses.
